UNITED STATES PATENT OFFICE

WILLIAM F. GONGAWARE, OF SANTA MONICA, CALIFORNIA

FIRECRACKER TUBE ROLLING MACHINE

Application filed August 24, 1931. Serial No. 558,879.

This invention relates to a machine and a method for making tubes especially for the manufacture of Chinese firecrackers.

It is an object of the invention to provide a method and machine for the rapid and practical production of jackets or tubes to be filled with an explosive. A further object is to provide for the production of a tube which is of convolute-winding and is a thoroughly compacted structure so as to have an inherent toughness especially desirable in fire-cracker structure so as to obtain a loud detonation when exploded.

An additional object is to provide a means and method for production of a fire-cracker tube in which there is made a crimp or fold of the strip of material such, for instance, as ribbon paper although it is to be understood that the blank material used in the production of the tube may be of any desired character, property or nature. In this connection, an object of providing a crimp or fold in the wound coils of the strip is to obtain a greater toughness of the tube and thereby to increase the noise of explosion when the fire-cracker is ignited.

A further object is to provide a continuous action machine in which the ribbon or strip of stock is continuously advanced from a supply roll and is cut into pieces or strips of predetermined length and are fed to a core and platen means whereby the leading end of the advanced strip or blank of stock is caught up and coiled on the core and subjected to a spinning motion by action of the platen and is concurrently subjected to a compacting or compressing effect by a pressure means. Further, means are provided whereby to apply a liquid adhesive to the trailing end of the winding blank so that the trailing end will be pasted down on the body of the tube in due sequence, during operation, and means are provided to effect the automatic ejection of the finished tube from the machine.

To obtain economical operation, it is an object to provide a multiplex type of machine for the concurrent spinning or coiling of a plurality of the fire-cracker tubes at one time, though it is to be understood that the ma-

chine may embody means for producing one or more tubes concurrently.

The invention consists in certain advancements in this art as set forth in the ensuing disclosure and having, with the above, additional objects and advantages, and whose construction, combination and details of means, and the manner of operation will be made manifest in the description of the hereinafter illustrative embodiment; it being understood that modifications, variations and adaptations may be resorted to within the scope, principle and spirit of the invention as it is more directly claimed hereinafter.

Figure 1 is a plan of the machine. Figure 2 is a side elevation, looking in the direction of the arrow 2, Fig. 1. Figure 3 is a side elevation looking toward the machine in the direction of arrow 3, Fig. 1. Figure 4 is an end elevation of the discharge end of the machine; parts being broken away and others omitted, for clarity. Figure 5 is an elevational and partial cross-section looking toward the pasting apparatus. Figure 6 is a diagrammatic view of the action of the parts in feeding and crimping a strip of stock. Figure 7 is a sectional detail of the core, elevator device. Figure 8 is a perspective of a rolled, fire-cracker tube as produced by the machine.

In the present apparatus a reel of ribbon-like stock S of suitable material, preferably tough paper is placed upon suitable bearings 2 conveniently disposed on a frame 3; the strip feeding to a guide trough 4 of complementary width to a strip of stock which passes under guard bridges 5 and 5'.

In the present apparatus the machine is designed for handling a plurality of strips S arranged in parallelism and passing to duplicate rolling and operating mechanism to produce a suitably sized fire-cracker tube T, Fig. 8.

Each strip S passes to and between an upper cutter cylinder 6 and a lower coacting feed roller 7; these being provided, preferably with friction faces 8 to effectively engage the strip S and feed it to a fixed guide box 10 from whence it passes over a flipper arm 11 and under a fountain cylinder shell 100

12 above which is a fountain cylinder 13 receiving a liquid adhesive from a fountain 14.

5 The advancing strip S, moving under the shell 12, enters a guide channel or conduit 15 provided on an oscillating carrier 16 by which the discharge end 17, Fig. 6, of the guide conduit 15 is normally held in lowered position just over a friction platen 18, fixed 10 on a spinning shaft 19.

Parallel and adjacent to the platen 18 is a shaft or core 20 which is adapted to bodily shift laterally and also to freely rotate. This is so disposed that the leading end of the 15 strip S will pass under it while in engagement with the spinning platen 18.

Means are provided to facilitate the coiling or winding of the strip of stock S onto the core 20 and this is shown as including an 20 endless, travelling belt 21 which bends around a fixed axis drive drum 22 on a spinning shaft 23. The loop of the belt 21 also passes around a guide roller 24 and from thence to a parallel and somewhat spaced 25 guide roller 25; these rollers being mounted on an oscillating carrier 26 fixed on a rocker shaft 27 which is parallel and close to the driving drum shaft 23.

When the roller carrier 26 is in lower effective position, Fig. 6, the belt 21 is pressed 30 in an arc between the rollers 24 and 25 and against the interposed core 20 or windings of the stock strip S; the belt 21 therefore constituting a presser device pressing the 35 winding tube, on the core 20, against the spinning platen 18; both the driving presser belt 21 and the platen 18 coacting to spin and to compactly wrap the windings of the tube on the core 20.

40 A feature of the present method of making the fire-cracker tube is to form a crimp or fold transversely across the strip as it passes between the core 20 and the spinning platen 18 and this is accomplished by a 45 crimping blade 30 which is adapted to be moved down in front of the issue end 17 of the feed conduit 15 and this is adapted to rise as the crimping blade 30 acts thereby to form a crease which will be rolled under the 50 leading end of the strip S coming from the conduit 15.

It is desirable to paste down the trailing end S' of the strip being wound on the core 20 and this is done by an upward movement 55 of the flipping blade 11 to bring the end S' against the paste roller 13 at a moment subsequent to the action of the crimping blade 30. Therefore as the trailing end S' of the strip passes between the wound tube on the 60 core and the platen 18 the trailing end will be pasted down under pressure of the presser belt 21 which then is immediately thrown upward to the position shown in Fig. 3 so as to clear the tube of paper which is on the 65 core 20.

As the roller carrier 26 lifts the belt 21 out of the way a finger 31 attached to the rocker shaft and acting with it presses an elevator 32 inwardly so that its wedge 33 70 will pass between the core 20 and the platen 18 so as to separate the tube T Fig. 7 from the platen and enable the ejection of the tube T endwise from the core 20. After the tube T has been ejected the elevator 32 is retracted by the finger 31 to allow the core to again bear on the platen 18 in readiness for the next incoming strip S.

Driving and actuating means and devices for the above described mechanisms will now be described in detail; the upper feed roller 6, which has a suitable cutter 6', is secured on a shaft 35 on which is fixed a driving pulley 36 engaged by a driving belt 37 looped on a driving pulley 38 which is fixed on the main, or drive shaft 40 having suitable bearings 41 conveniently supported on a frame structure 42. The lower feed roller 7 is mounted on a yieldably mounted shaft 43 in suitable bearings in the frame 3 and has a mortise 7' to receive the cutter 6' for effective separation of the strip S while the leading end thereof is engaged between the core 20 and the platen 18 and the tube started on the platen.

It is desirable to momentarily put a drag 95 on the strip S at the instant of action of the cutter 6' and for this purpose a brake device 44 is provided and is actuated by a striking finger 45 fixed on the shaft 35 and being positioned to apply the brake device 44 to the strip S at the moment of action of the cutter 6'; the brake being automatically retracted by a spring 46 operating on a part of the brake device.

The fountain or paste roller 13 is fixed 100 on a spinning shaft 47 which is connected by a suitable transmission means 48 to the main shaft 40 so that the fountain roller 13 is constantly rotating.

The platen shaft 19 is constantly rotated 105 by a suitable transmission means here shown as including a transmission belt 49 engaging a pulley 50 fixed on the shaft 19 and a relative pulley 51 fixed on the main shaft 40.

Power is transmitted to the shaft 23 of the spinning roller 22, to drive 21, by a suitable transmission from main shaft 40 and shown as including a belt 52 from main shaft pulley 53 to pulley 54 fixed on the spinning 115 shaft 23.

In the present structure the several shafts 19, 23, 35, and 47 extend across the top bed structure of the frame 42 and are mounted in suitable bearings thereon and are adapted 120 for the operation of the duplicate feeding, winding, and crimping mechanisms above described; though it is to be understood that only a single train of mechanism may be employed if so desired for the pro- 125

duction of only one tube T at a time in the machine.

Referring to Fig. 2; the rock-shaft 27 to which the roller carrier 28 is fixed is provided with a lever arm 55 connected to the upper end of a push rod 56 which is normally pulled downward by a spring 57 and is connected to a contiguous arm 58 of a lever 59 having pivot 60 in a suitable bearing part 10 of the frame and which lever is engaged by an actuating crank 61 which is secured on a timing, countershaft 62, mounted in suitable bearing parts and on which is fixed a gear 63 engaging and driven by a complementary gear 64 fixed on the main shaft 40.

The crank 61 and the lever 59 and link 56 form means whereby roller carrier 28 is intermittently raised to a position shown in Figs. 2 and 3 to lift the belt 21 out of the way of a set of ejector bars 65 whose lower ends straddle the core 20 at positions near the inner ends of the tube being wound on the core. The ejector bars 65 are shown in Fig. 4 as fixed to slides 66 and 67 operating in opposite directions on a fixed rail 68 whose ends are fixed on brackets 69. The ejector slides 66-67 are retractively connected by a suitable spring 70 and their outer ends are engaged by upright side levers 71-72 which have pivots 73 in the sides of the frame 42; the lower ends of the ejector levers 71-72 being pivotally connected at 74 to the outer ends of reciprocating rods 75-76 which are mounted in appropriate bearings 77. On the inner ends of the reciprocating rods 75-76 are rollers 78 which are pulled, through action of the spring 70, against appropriate cams 79 which are fixed on a cam shaft 80 in suitable journals and having a large gear 81 engaging and driven by a pinion 82 on the main shaft 40.

The cam shaft 80 is so timed as to oscillate the ejector levers 71-72 and shift the ejector 65 outwardly to eject the finished tubes 45 from the core 20 immediately following the lifting motion of the presser belts 21 by action of the push rod 56.

Also secured on the rock-shaft 27 Fig. 2 is an arm 83 forming means whereby a set 50 of gates 14' of the paste fountain 14 are momentarily opened at about the time the presser belts 21 are elevated for the purpose of discharging a small quantity of adhesive fluid onto the rotating paste roller 13. The arm 83 in moving down engages a cooperating arm 84 fixed on a transverse rock-shaft 85 on which are secured the carriers 16 of the guides or conduits 15 leading to the platen 18. The downward movement of the arm 84 serves to lower the guide channels or conduits 15 to a position leading the incoming strip or strips S, one in each guide, to the top 60 of the platen 18 and under the empty core 20; this being pressed downward by light springs 20' Fig. 7. Secured to the rock-

shaft 85 is an arm 86 carrying a pawl 87 which acts on the up stroke of the arm 86 to engage a gate lever 88 having a shaft 89 journalled on the paste fountain 14 and to which are connected gates 14 closing the bottom outlets of the fountain 14. The gate arm 88 is pulled to gate-closing position by a spring 90; the opening action of the pawl 87 being momentarily on the gate lever 88 during upward stroke of the arm 86; the return stroke passing the pawl without operating effect on the gate arm 88.

As the end S' of a strip of paper passes over the flipper 11 this is actuated by means of a link 11' whose lower end is connected to a lever 91 having a pivot 92 and provided with a cam pin 93 engaged by a crank pin 94 fixed on the timing shaft 62 and which operates, as it engages the pin 93 to push the flipper rod 11 upwardly and thereby swing the flipper 11 upwardly to carry the trailing end S' of the strip against the paste roll 13. The flipper and its connected link 11' are retracted instantly by a spring 95 as soon as released from the actuating crank 94.

For the purpose of intermittently moving the crimping blade 30 down to crimp the strip passing under the core 20 the blade is connected to a cross-head 100 fixed to a plunger 101 on which is secured a tappet 102 and adapted to be engaged in a crank pin 103, here shown as carried by the gear 63. The plunger 101 is normally elevated by a spring 104, Fig. 6, to a clear position. As the plunger moves down it carries a finger 105 against a shoulder on a lever 106 pushing one end of this lever down and the opposite end up so as to thrust a link 107 upward. This link is connected at 108 to the rocking carrier 16. Therefore as the crimping blade 30 is moved down by the plunger 101 this acts through the link 107 to raise the issue end 17 of the guide conduit 15 to facilitate crimping action. The guide conduits 15 are depressed to normal position by action of the rocker shaft 85 when the lever 84 is actuated by the push rod 56; this action lifting the presser belts 21 to permit operation of the ejectors 65.

The rock-shaft 85 and its attached conduits 15 are frictionally retained in position with the guides 15 in normal feeding position by a brake device 84' fixed on the arm 84.

The presser belt 21 is drawn down against the core 20 by means of a spring 27' suitably connected to the plate 26.

What is claimed is:

1. A machine for making a tight-wound, convolute-layer tube including a turnable core, means to feed a flat strip blank thereto, a spinning, friction platen, means to press the coiling tube to the platen, and means to eject the tube from the core.

2. A machine for making a tight-wound, convolute-layer tube including a turnable core, means to feed a flat strip blank thereto,

- a spinning, friction platen, means to press the coiling tube to the platen, and means to eject the tube from the core; said pressing means including an endless traveling presser belt to arch on the coiling tube on the core. 5
3. A machine for making a tight-wound tube, including a spinning, friction platen, a turnable core adjacent to the platen, means to feed a strip of stock to the platen and core, 10 means to compress the winding tube layers, and means to eject the finished tube. 15
4. A machine for making a tight-wound tube, including a spinning, friction platen, a turnable core adjacent to the platen, means to feed a strip of stock to the platen and core, 20 means to compress the winding tube layers, means to eject the finished tube, and means to move the compressing means to ineffective position before the ejector acts. 25
5. A machine for making a tight-wound tube, including a spinning, friction platen, a turnable core adjacent to the platen, means to feed a strip of stock to the platen and core, 30 means to compress the winding tube layers, means to eject the finished tube, and means to move the compressing means to ineffective position before the ejector acts; said platen including a friction device to spin the winding tube, and means to move the tube from contact with the friction device before the 35 ejector acts. 40
6. A machine for making a tight-wound tube, including a spinning, friction platen, a turnable core adjacent to the platen, means to feed a strip of stock to the platen and core, 45 means to compress the winding tube layers, means to eject the finished tube, and means to move the compressing means to ineffective position before the ejector acts; said platen including a friction device to spin the winding tube, means to move the tube from contact with the friction device before the 50 ejector acts, and means to move the wound tube from the platen and the compressing means out of effective position before the 55 ejector acts. 60
7. A tube winding machine including means to build a convolute-wound tube from strip stock, means to crimp the ribbon during the winding operation, and means for subjecting the ribbon to a compacting pressure to crease down the crimp fold on the tube windings. 65
8. A tube winding machine including a turnable core, a spinning, friction platen adjacent to the core, means to feed a strip of ribbon-like material to the platen and the core, a pressure device adjacent to the core to press on the winding strip and compact it, 70 and means for forming a fold in the strip as it passes between the said device and the body of the tube. 75
9. A tube winding machine including a turnable core, a spinning, friction platen adjacent to the core, means to feed a strip of ribbon-like material to the platen and the core, a pressure device adjacent to the core to press on the winding strip and compact it, 80 and means for forming a fold in the strip as it passes between the said device and the body of the tube; said means including a blade movable against the strip to form a fold in it. 85
10. A tube winding machine including a turnable core, a spinning, friction platen adjacent to the core, means to feed a strip of ribbon-like material to the platen and the core, a pressure device adjacent to the core to press on the winding strip and compact it, 90 and means for forming a fold in the strip as it passes between the said device and the body of the tube; said means including a blade movable against the strip to form a fold in it and a guide channel coacting with the blade to make the fold. 95
11. A fire-cracker tube machine including a laterally shiftable, turnable core, means to feed a strip end thereto, a spinning platen, means pressing the winding on the core to the platen to effect rotation, means to laterally shift the loaded core from the platen, and means to eject the tube from the core. 100
12. A machine for winding fire-cracker tubes, having winding core, means to spin the core as a strip of stock is fed thereto, means to apply adhesive to the trailing end of the strip, means to press the adhesive zone of the strip to the wound tube on the core, and means for making a crimp in the strip prior to pasting down the trailing end. 105
13. In a tube making machine, a winding core, a guide channel leading a strip end thereto, means to spin the core to wind the tape thereon, a blade operative to fold a crimp in the strip as it winds on the core, and means to shift the said channel to facilitate the crimping action. 110
